GARMENT-SUPPORTING FIXTURE.

1,131,722.

Specification of Letters Patent.

Patented Mar. 16, 1915.

Application filed September 16, 1914. Serial No. 861,954.

To all whom it may concern:

Be it known that I, FRANK W. MEYER, a citizen of the United States, and a resident of Oshkosh, in the county of Winnebago and State of Wisconsin, have invented certain new and useful Improvements in Garment-Supporting Fixtures; and I do hereby declare that the following is a full, clear, and exact description thereof, reference being had to the accompanying drawings, and to the letters of reference marked thereon, which form a part of this specification.

This invention relates to improvements in garment supporting fixtures and more particularly to devices of the character described of the extensible or telescoping type and applicable for use in connection with wardrobe trunks or other compartments suitable for the storage or hanging of garments.

Among the objects of the invention is to provide a simple and efficient device for supporting garments, or the hangers upon which the garments are suspended and further, a device capable of permitting said hangers to be withdrawn from the trunk or compartment, to a position permitting convenient access to the garments supported thereby.

Further objects of my invention will be apparent as I proceed with a detailed description of a device embodying the features of my invention, the same being fully illustrated in the accompanying drawings, in which—

Figure 1 is a view in top plan view of the garment supporting fixture with hinged top removed and showing the slideable arms in extended position. Fig. 2 is a sectional view taken on line 2—2 of Fig. 1, of one of the supporting members in side elevation. Fig. 3 is a view in longitudinal section taken on line 3—3 of Fig. 4, showing construction of the members and of the locking or catch member. Fig. 4 is a view in cross section taken in line 4—4 of Fig. 3. Fig. 5 is a detailed view in elevation of a supporting member and arm showing a modified construction of the rib of said arm.

Referring now to the accompanying drawings, the garment fixture therein illustrated is shown as fixed or secured within the upper portion of the garment containing section or compartment of a wardrobe trunk having an open or hinged top or upper wall. The compartment or section is formed by the walls of the trunk comprising a vertical rear wall

9, side walls 10, 10, and the movable or hinged top wall 11; the latter being connected to the rear wall by means of hinges 11^a, 11^a, and adapted to swing upwardly when the trunk is in open position. The compartment is shown in open position, the remaining portion of the trunk 8 being swung back, thereby permitting outward movement or extension of the movable supporting members of the fixture so that access may be had to the garments supported thereon, in the manner usual with garment fixtures of the extensible type.

The supporting fixture comprises in general, two slotted or grooved tubular supporting members 12, 12, supported in fixed positions upon opposite sides of the compartment and arranged adjacent to and in parallel relation with the opposite side walls 10, 10, and likewise in parallel relation with each other. As shown, said tubular members extend from the rear wall 9 to the forward margin of the side walls 10, 10, the tubular members being open at their forward ends. Within the tubular members 12, 12, are mounted slideable rods or extensible arms 13, 13, adapted to be moved outwardly or inwardly through the open ends of the tubular members.

The tubular supporting members are rigidly connected together and to the walls of the compartment or trunk by means of supporting brackets constructed and arranged as follows: At the rear of the compartment is provided a transverse bar 14 extending by preference entirely across the rear wall 9, the ends thereof being bent to form arms 14^a, 14^a, extending at right angles to the main portion of the bar. Said bar, with its bent end portions, engages the rear and side walls and is fixed thereto by means of a suitable number of screws 15. This bar supports the rear ends of the tubular members 12, 12, which are connected thereto, preferably by the provision of apertures in said bar, into which extend the ends of said tubular members, a connection being made between the members by upsetting the ends of the tubular members or in any other suitable or well known manner. Obviously single or disconnected brackets might be employed to support the rear ends of the tubular members, but the use of the bar as described is more desirable in that it forms a connection between the tubular members 110

12, assuring the maintenance of the proper spacing, and parallel relation of said members. Furthermore, the provisions of the continuous connecting and supporting bar adds a considerable degree of rigidity and stability to the fixture as a whole, and also renders the assembled device a complete unit or combination of connected elements. The use of a bar 14 extending entirely across the rear wall and connected to the rear and side walls of the trunk is particularly advantageous in connection with the so called open top trunks, in that the bar serves to strengthen or reinforce the end of the trunk adjacent to the hinged top. In this manner the bar gives added strength throughout that portion of the trunk that must be necessarily weakened to some degree by reason of the particular construction employed, and thereby acts to resist the crushing or distorting of the walls of the trunk by excessive pressure or violent shocks, as well as eliminating the liability of damage to the garment supporting fixture by breakage or displacement of the supporting member.

The forward ends of the tubular members are supported by separate brackets 16, 16, which are secured to the side walls 10, 10, adjacent to their forward margins. These brackets are provided with inwardly extending arms 16^a, 16^a, curving upwardly to a slight degree and engaging the under surfaces of the tubular supporting members 12, 12, the ends of said arms having a concave seat in which rests the ends of said tubular members. A screw 17 extends through the ends of each of the brackets 16, and engages the adjacent portion of each tubular member, thus securing the forward end of each of said members rigidly to each bracket. The combination of the bar 14 attached to the rear and side walls, the brackets 16 attached at the margins of the side walls and the supporting members 12, 12, rigidly connected at their ends to said bar and brackets, forms in effect a strengthening member extending around three sides of the compartment, thus adding materially to the strength of the trunk.

In referring in detail to the construction of the tubular supporting members 12, 12, the sliding arm members 13, 13, and their component parts, but one of the same will be described since both sets of members are identical in construction and operation.

Each tubular supporting member 12 is provided along its uppermost portion or surface, with a longitudinally disposed slot 18, which opens upwardly and extends from the margin of the opening at the forward end of said tubular member and terminates a short distance from the rear end of the same. Each extensible or slidable arm 13, herein before mentioned is slidably mounted within a corresponding tubular supporting member and is provided upon its upper surface with a longitudinally extending rib or projection 19, said rib extending from the forward end of the arm and terminating at a point a short distance from its rear end, said rib being preferably of a length substantially equal to that of the slot 18. This rib is adapted to engage and slide in the slot 18 of the tubular supporting member and is so formed or dimensioned as to fit snugly within said slot and to have its upper or outer face flush with or slightly above the level of the edges or the top surfaces of the tubular member adjacent to the margins of the slot. At the outer or front end of the sliding arm 13, is provided an enlarged head, preferably in the form of a disk 20, slightly greater in diameter than the tubular supporting member 12. This disk or head acts as a stop to limit the inward movement of the arm, by its contact with the end of the tubular member, and further to retain the garment hangers upon the arms.

As a means for limiting the outward movement of the sliding arms the following construction is employed. At or near the inner end of the arm 13, and upon its lower surface is provided a slot 21, opening downwardly and rearwardly as shown in Fig. 3. Within this slot is mounted a locking dog or catch 22, the same being pivoted upon a pin 23 extending transversely of and located near the rear end of the slot. The greater length or body portion of the dog is located forwardly of its pivoting point, and is adapted to be partially rotated or to swing through a limited distance in a vertical plane. In the lower or under surface of the tubular supporting member is provided a comparatively short slot 24, (Fig. 105 3) the same being located adjacent to the forward end of said member and immediately to the rear of the forward bracket 16. This slot is also located in alinement with the slot 21 of the sliding arm, so that when said arm 13 is drawn outwardly so that the slots register one with the other, the forward portion of the dog is free to drop downwardly into the slot 24 of the tubular supporting member, whereupon its forward margin 111 comes in contact with the forward end of the said slot, thus preventing further movement of the sliding arm 13 in a forward or outward direction.

The locking dog 22 assumes an inclined 120 position when in lowered position or in locking engagement with the slot 24, therefore the front or contact face 22^a of said dog is slightly beveled so that it presents a vertical face when in contact with the slot. In 125 order to limit the downward movement or drop of the dog, the same is provided upon its upper surface and throughout the portion thereof rearwardly of its pivoting point with another beveled surface 22^b, which co- 130

acts with the adjacent surface of the slot 21, thus acting as a stop surface. It is obvious that the dog 22 is contained entirely within the slot 21 when the sliding arm is in 5 all positions except that in which the slot 21 thereof passes over the slot 24 of the supporting member, and hence the dog is inoperative except when said arm 20 is extended or drawn outwardly to its extreme 10 length.

The operation of the dog is entirely automatic in that it drops by gravity into locking position during the forward movement of the arm and is forced upwardly into non-operative position simply by the contact of 15 its inclined bottom edge or margin with the inner end of the slot 24 as the arm is moved inwardly. When in locking position the lower portion of the dog extends slightly 20 below the slot 24 so that to remove the arm entirely from the tubular supporting member, it is easily accessible to the fingers for 25 the purpose of moving the same upwardly into locking position, whereupon the arm may be drawn forwardly and from the tubular member.

As before suggested, the tubular members 12, 12, and slideable rods or arms 13, 13, are adapted to support a plurality of garment hangers 25, the garments being hung or suspended therefrom. The upper or fixture engaging portion of the hanger comprises a transverse member 25^a which extends between the supporting members, the 30 ends being provided with semicircular notches 25^b, adapted to engage the upper surfaces of the supporting members, (Fig. 4.)

When the trunk or compartment is closed 40 the supporting fixture is in contracted position, that is: the extensible or sliding arms 13, 13, are moved inwardly within the supporting members. The hangers are therefore, positioned within the compartment 45 and engage the tubular supporting members. To render the garments accessible when the trunk or compartment is open, the extensible arms 13, 13, are moved longitudinally forward or outward so that they 50 project beyond the opening of the compartment. The hangers and garments suspended on the tubular members 12 and rods 13 may therefore, be carried or caused to 55 slide forwardly from the interior of the space between the side walls and on to the extensible arms 13, 13.

The purpose of the longitudinal slots in 60 the upper surfaces of the tubular supporting members and the ribs upon the sliding rods extending upwardly into said slots is now apparent and is of material advantage in the operation of the device and the manipulation of the hangers. The ribs constitute tracks or bearing surfaces upon the 65 sliding rods which serve when said rods are

in extended position, to form a continuous, smooth and uninterrupted bearing surface for the hangers extending the entire length of the supporting members and arms by reason of the fact that the upper surfaces of 70 the ribs lie in approximately or very slightly above the same plane as that of the upper or bearing surfaces of the tubular supporting members. Thus when the hangers are moved forwardly or rearwardly with respect 75 to or on the tubular supporting members and sliding rods or on to the tubular members when the rods are extended, said hangers slide along a substantially continuous and level supporting surface, whereas in 80 the absence of the ribs, the hangers would necessarily be moved upwardly or downwardly over an obstruction or shoulder formed by the ends of the tubular supporting members, said obstruction being obviously present by reason of the greater 85 diameter of said supporting members and sliding rods. The provision of the rib therefore, permits the hangers to be easily moved forwardly and rearwardly without liability 90 of becoming jammed or otherwise hindered in their movement by reason of the presence of the construction before pointed out, as is the case in the ordinary known forms of garment supporting fixtures. 95

The rib 19 has herein before been described as having its upper surface flush with or slightly above the upper surface of the tubular supporting members. A tubular supporting member is circular in cross section as already stated. Hence the upper surface of the rib would project slightly above the longitudinal plane of the margins of the longitudinal slot in the tubular supporting member. As a result therefore, the 100 hangers when engaging the tubular supporting members, with the extensible arms in contracted position as when the trunk or compartment is closed, would rest upon the ribs by reason of the fact that a portion of 110 each rib projects above the adjacent edges of the grooved portion of the corresponding tubular supporting member. By reason therefore, of the contact between the garment hangers and the upper surfaces of 115 said ribs, said hangers would tend to be carried outwardly to their extended position. In this manner the ribs act also as a supporting surface for the garment hangers and aid to carry them forwardly with the 120 sliding rods whereas in the absence of the ribs, two operations would be necessary in operating the device, namely, drawing out the rods or arms and then sliding the hangers and garments outwardly upon the arms. 125 As a further improvement in the construction hereinbefore set forth, it is found desirable to bevel or slightly incline downwardly, the rear end portion of the rib as shown at 27 in Fig. 5, thus the forward 130

4
ends of the tubular supporting members and the rear portions of the ribs are in substantially flush relation when the extensible rods are extended so that a smooth bearing surface is provided at the junction of the supporting members and arms, with the accomplishment of the same results as in the first mentioned construction. In order to lock the top and side walls of the trunk when the top is closed, I provide a snap latch device 40 of the usual construction. (See Fig. 4.) As shown, said latch device comprises a spring pressed bail 41, pivotally mounted on the side wall 10 of the trunk and adapted to be swung into an upright position extending over and having locking engagement with, a keeper 42, mounted on the depending side flange of the top or lid 11. As this latch device is of the usual type employed on trunks of this character, the operation of such device is well known and needs no description.

25 A garment hanger made in accordance with the feature of my invention is exceedingly light and compact in structure in that all of the members are located in the same plane, and hence occupies the minimum amount of space within the trunk or compartment. Furthermore, the absence of a 30 transverse member connecting the outer ends of the sliding rods permits easier access to garments supported thereby and less annoyance in removing the hangers from, or placing them upon the supporting fixtures.

35 I claim as my invention:

1. In a garment supporting fixture, the combination of a supporting member provided with an upwardly opening longitudinal slot, and an arm in slidable connection 40 with said supporting member and provided with a longitudinal upwardly extending rib adapted to project into said slot, the upper surface of said rib being substantially flush with the adjacent upper surface of said supporting member.

2. In a garment supporting fixture, the combination of a tubular supporting member provided with an upwardly opening longitudinal slot, a rod slidably mounted in said tubular supporting member and provided with a longitudinally extending rib adapted to project into said slot, the upper surfaces of said supporting member and rib being substantially flush.

55 3. In a garment supporting fixture, the combination of a plurality of tubular supporting members, each being provided with an upwardly opening longitudinal slot, a rod slidably mounted in each of said supporting members and each rod being provided with a longitudinally extending rib adapted to project into the slot of its supporting member, the upper surfaces of said supporting members and ribs being substantially flush, and means for supporting said

tubular members in fixed and parallel relation.

4. In a garment supporting fixture, the combination of a plurality of supporting members, spaced apart and arranged in parallel relation, each of said supporting members being provided with an upwardly opening longitudinal slot, a rod slidably mounted in each of said supporting members and adapted to be extended from one end thereof, each of said rods being provided with a longitudinal rib adapted to project vertically into the slot of its supporting member, and a fixed bar extending between and rigidly connecting said supporting members.

5. In a garment supporting fixture, the combination of two tubular supporting members, spaced apart and arranged in parallel relation, each of said supporting members being provided with an upwardly opening longitudinal slot, an arm slidably mounted in each of said supporting members and adapted to be extended from one end thereof, each arm being provided with a longitudinal rib adapted to project into the said slot of its supporting member, the upper surfaces of said ribs and tubular supporting members being substantially flush, and means for supporting said tubular members comprising a fixed bar extending between and rigidly connecting said supporting members at one end thereof, and brackets connected with the opposite ends of said supporting members.

100 6. In a garment supporting fixture, the combination of a tubular supporting member provided with an upwardly opening slot, an arm slidably mounted within said supporting member and extensible from one end thereof, said arm being provided with a longitudinal rib adapted to project into said slot, the upper surface of said rib being substantially flush with the upper surface of said supporting member, and means for limiting the endwise movement of said arm in one direction comprising a dog pivotally mounted on said arm at one end thereof and adapted to engage the tubular supporting member adjacent the opposite end thereof.

110 7. In a garment supporting fixture, the combination of a supporting member provided with an upwardly opening slot, extending substantially throughout its length, an arm slidably mounted in said supporting member and extensible from the forward end thereof, said arm being provided with a longitudinally extending rib, adapted to project into said slot and slightly above the surface of said slotted supporting member, said rib having the surface of its rear portion substantially flush with the upper surface of said supporting member.

120 8. A garment supporting fixture for a

trunk, comprising a supporting member adapted to be secured in fixed relation in the wardrobe compartment of said trunk, and an extensible member having endwise sliding connection with said supporting member; the upper surface of said extensible member being substantially flush with upper surface of said supporting member, whereby the upper or supporting surfaces of said supporting and extensible members will be continuous and unbroken, when the

extensible member is extended beyond one end of said supporting member.

In testimony that I claim the foregoing as my invention I affix my signature in the 15 presence of two witnesses, this 11th day of September A. D. 1914.

FRANK W. MEYER.
